United States Patent

Des. 237,659
Patented Nov. 18, 1975

237,659

TOOTHBRUSH AND HOLDER THEREFOR

Burton C. Meyer, Downers Grove, and Joseph M. Burck,
Chicago, Ill., assignors to Marvin Glass & Associates,
Chicago, Ill.

Filed Dec. 6, 1974, Ser. No. 530,056

Term of patent 14 years

Int. Cl. D4—02

U.S. Cl. D4—18

FIG. 1 is a perspective view of a toothbrush and holder therefor showing our new design;

FIG. 2 is a side elevational view thereof, on an enlarged scale;

FIG. 3 is a top plan view thereof;

FIG. 4 is front elevational view thereof; and

FIG. 5 is a rear elevational view thereof.

The side opposite that of FIG. 2 is identical to that shown.

We claim:

The ornamental design for a toothbrush and holder therefor, as shown and described.
